UNITED STATES PATENT OFFICE.

PAUL PONDORF, OF GOESSNITZ, GERMANY.

ANNEALING-FURNACE FOR CARTRIDGE-CASES.

SPECIFICATION forming part of Letters Patent No. 643,751, dated February 20, 1900.

Application filed March 3, 1899. Serial No. 707,661. (No model.)

To all whom it may concern:

Be it known that I, PAUL PONDORF, manufacturer, a subject of the Emperor of Germany, residing at Goessnitz, Saxony-Altenburg, German Empire, have invented certain new and useful Improvements in Annealing-Furnaces for Cartridge-Cases; and I do hereby declare the following to be a full, clear, and exact description of the invention, such as will enable others skilled in the art to which it appertains to make and use the same.

This invention relates to apparatus for annealing metallic cartridge-cases; and it consists in the novel construction and combination of the parts hereinafter fully described and claimed.

In the drawings, Figure 1 is a vertical section through the apparatus. Fig. 2 is a front view of the feed mechanism. Figs. 3 and 3^a are respectively detail plan views of the plates *b* and *a* drawn to a smaller scale. Fig. 4 is a plan view of the apparatus.

A is a stand which supports a stationary plate or support *a* for supporting the cartridge-cases while being annealed. The plate *a* is supported in any approved manner—as, for instance, by distance-pieces *a'*, inserted between it and the stand. A rotary plate or disk *b* is secured on a vertical shaft *b'*, which is journaled in the plate *a*. A shaft *d* is journaled in the stand *A* under the plate *a* and is driven continuously by a belt-pulley *f*. The shafts *b'* and *d* are operatively connected together by beveled toothed wheels *c* and *c'*; but the plate *b* may be revolved continuously by any other approved feed mechanism. The plate *a* has a discharge-hole *a'*, and the plate *b* has a series of holes *k*, arranged in a circle about the shaft *b'* and at the same distance from it as the hole *a'*. A perforated gas-pipe *x* is supported above the plate *b* and extends around the greater part of its periphery adjacent to the holes *k*.

The cartridge-cases *q* are dropped one by one into the holes *k*, so that their bases rest on the plate *a* and their smaller ends project above the plate *b* in front of the gas-jets, as shown at the left hand in Fig. 1. The rotary plate *b* moves the cartridge-cases over the plate *a* and finally drops them one by one through the hole *a'* into the discharge-chute

y. The smaller ends of the cartridge-cases are heated by the gas-flames, so that their annealing is effected.

The cartridge-cases are fed one by one to the plate *b*. A feed-chute *g* is supported from the plate *a* by a bracket *g'* and has arms *s* secured to its lower end. A shaft *h'* is journaled in the arms *s* and has a star-wheel *h* and a ratchet-wheel *n* secured on it. The wheel *h* is arranged to one side of the middle of the feed-chute, and *l* is a forked rest secured to the bracket *g'* and projecting in front of the bottom of the feed-chute on the other side of its middle portion from the star-wheel. A conical guide *i* is secured to the bracket *g'* on the other side of the star-wheel from the rest *l*, and the lower orifice of the guide is arranged to register with the holes *k* in the plate *b*. The star-wheel is revolved step by step, and the cartridge-cases slide down the feed-chute with their bases arranged on the same side as that on which the guide *i* is located. Each cartridge-case *q* slides onto the rest *l* and is engaged by two of the teeth 75 of the star-wheel, as shown by dotted lines in Fig. 4. When the star-wheel is moved in the direction of the arrow in Fig. 1, it tilts up the lowest cartridge-case, so that it drops through the guide *i* and the hole *k* under it 80 and then rests base downward on the plate *a*.

The star-wheel is moved step by step by a pawl *m*, which is pivoted to one end of a lever *o* and which engages with the ratchet-wheel. The lever *o* is pivoted on a pin *p*, 85 projecting from an arm *p'*, secured to the bracket *g'*. The other end of the lever *o* is provided with a tooth *o'* which rests on the plate *b*, and *t* is a spring secured to the bracket *g'* and to the lever *o*, and which operates to hold 90 the tooth *o'* in contact with the plate *b*.

A series of projections *k'* is provided on the plate *b*, which engage with the tooth *o'* and move the lever *o* in one direction.

The lever *o* is provided with a check-pawl 95 *o²*, which bears against the ratchet-wheel and prevents it from being turned too far at each stroke of the lever *o*.

When the spring *t* operates the lever *o*, the star-wheel tilts a cartridge-case down the 100 guide, and the motion of the plate *b* is preferably so timed that at that moment a hole *k*

is under the guide ready to receive the cartridge-case.

The cartridge-cases are moved in front of the gas-jets and are discharged by the plate 5 b, as hereinbefore described.

What I claim is—

1. In annealing apparatus, the combination, with a stationary support for the cartridge-cases, of a rotary plate provided with 10 a series of holes for engaging the cartridge-cases arranged over the said support, means for revolving the said plate, and a perforated gas-pipe extending circumferentially over the said plate for the greater part of a circle and 15 operating to heat the upper end portions of the cartridge-cases, substantially as set forth.
2. In annealing apparatus, the combination, with a rotary plate provided with holes for engaging with the cartridge-cases, a support 20 for the cases arranged under the rotary plate, and a heater above the rotary plate; of a guide which registers with the said holes, a feed-chute, and feed mechanism arranged at the bottom of the feed-chute and operating 25 to tilt the cartridge-cases so that they drop through the said guide, substantially as set forth.
3. In annealing apparatus, the combination, with a support for the cartridge-cases,

a heater, and a rotary plate provided with 30 holes for engaging with the cartridge-cases, and having projections spaced to correspond with the said holes; of a guide which registers with the said holes, and intermittently-operated feed mechanism actuated by the said 35 projections and operating to drop the cartridge-cases into the said guide, substantially as set forth.

4. In annealing apparatus, the combination, with a support for the cartridge-cases, 40 a heater, and a rotary plate provided with holes for engaging with the cartridge-cases; of a guide which registers with the said holes, a feed-chute, a rest at the bottom of the feed-chute, a star-wheel journaled at the bottom 45 of the feed-chute between the said rest and guide, and driving devices actuated from the said rotary plate and operating to revolve the star-wheel intermittently, whereby the cartridge-cases are tilted at the bottom of the 50 feed-chute and are dropped one by one through the said guide, substantially as set forth.

In testimony whereof I affix my signature in presence of two witnesses.

PAUL PONDORF.
